Corporation, Redwood City, Calif.

Filed May 27, 1970, Ser. No. 33,182

Term of patent 14 years

Int. Cl. D14—01

U.S. Cl. D26—14

The sole figure is a front, top and right side perspective view of a magnetic tape cassette machine showing my new design, the left side being a mirror image of the right side and the bottom and rear being conventionally plain.

I claim:

The ornamental design for a magnetic tape cassette machine, substantially as shown and described.
